UNITED STATES PATENT OFFICE.

JOHN W. HAWKINS, OF CUYAHOGA FALLS, OHIO.

ADJUSTABLE DIE-HOLDER FOR WIRE-DRAWING MACHINES.

SPECIFICATION forming part of Letters Patent No. 662,271, dated November 20, 1900.

Application filed June 18, 1900. Serial No. 20,707. (No model.)

To all whom it may concern:

Be it known that I, JOHN W. HAWKINS, a citizen of the United States, residing at Cuyahoga Falls, in the county of Summit and State 5 of Ohio, have invented a certain new and useful Improvement in Adjustable Die-Holders for Wire-Drawing Machines, of which the following is a specification.

My invention has relation to improvements 10 in die-holders for wire-drawing machines; and one object of my invention is to enable the die to be raised or lowered to bring the opening in the die near the horizontal line of the drawing-spool, especially when the die has 15 two or more openings in vertical alinement, and a further object is to tilt or incline the die, so that it will be exactly transverse to the line of draft.

To the aforesaid objects my invention consists in the peculiar and novel construction, arrangement, and combination of parts hereinafter described and then specifically pointed out in the claims, reference being had to the accompanying drawings, forming a part of 25 this specification.

In the accompanying drawings, in which similar reference-numerals indicate like parts in the different figures, Figure 1 is a side elevation; Fig. 2, a plan, and Fig. 3 a front 30 elevation.

Referring to the figures, 1 is a bed-plate or base with the central part cut away, leaving two projecting ends 2 2, curved upward and backward, forming hooks and having vertical 35 side wings 3 3. Two flat bars 4 4 are bent to form three sides of a parallelogram, with one end longer than the other, and these longer ends are bent to enter and be retained in the hooked ends 2 2 by pivots 5 5, which pass 40 through angle-plates 6 6, that in turn hold the longer ends of the bars 4 4 against lateral displacement. The bars 4 4 are united at the top by a cross-bar or bridge 7, secured by rivets 8, in which bridge is a screw-threaded 45 opening in which runs a hollow bolt 9, also internally screw-threaded to receive a bolt 10. The lower end of the bolt 9 is reduced and screw-threaded and carries a nut 11.

Mounted to slide vertically between the depending ends of the bars 4 4, which constitute ways or guides for the purpose, is the die-holding frame 12, which consists of a wide

flat bar bent into a parallelogram, with its upper ends overlapping and perforated to receive the reduced screw-threaded end of the bolt 9 and to be secured thereon by the nut 11. The frame 12 has slotted openings 13 at front and back in horizontal alinement. At the back end of the bed-plate 1 is secured a plate 14, its outer end bent up at an angle of 55 about forty-five degrees. The upper end of the bent portion of the plate 14 has a hole in which is a screw-threaded rod 15, adjustably retained by nuts 16 17. The opposite end of the rod 15 is forked and the ends bent and 60 hooked into holes in the bars 4 4. The die 18 is of the usual pattern and consists of a steel bar perforated at determined intervals with conical holes, one of which 19 is shown in Fig. 1. This bar may be of any length, the illustration 65 showing it broken at each end, and the holes will be of various sizes and usually arranged in horizontal and vertical rank.

The apparatus is pivotally connected with the wire-drawing bench by a bolt that passes 70 through a hole 20 in the plate 1, thus permitting the front part of the machine a lateral movement to adapt it to the line of draft of the wire.

In operation the die is placed in the frame 80 12 and secured by turning the screw 10 firmly against it. By turning the bolt 9 the frame 12 and die 18 can be raised to any desired height within the compass of the machine, and the angle of the frame 12 and die can be 85 regulated by the nuts 16 17, thus enabling the operator to secure both the proper elevation of the die and the exact angle to have the wire draw at a right angle to the face of the die.

90 I claim as my invention—

1. An adjustable die-holder for wire-drawing machines embodying a base or bed, with means for pivotally connecting it with the drawing-bench, vertical guides to receive a 95 die-frame arranged to be rocked to and from the wire-drawing spool, means for rocking and retaining said guides at any desired angle, a die-frame arranged to move in said guides, a screw to adjust the height of said die-frame, 100 and means for locking a die therein, all constructed and arranged substantially as shown and described.

2. The herein-described die-holder for wire-

drawing machines consisting of a base or bed, with upward-turned hooks at the front and lateral wings and a raised portion at the back to receive an adjusting-screw, in combination 5 with parallel guides arranged to be secured in said hooks, a bridge to unite said guides, a bolt resting in an opening in the raised portion of said base, connected with said guides and provided with adjusting-nuts to rock said 10 guides, a die-holding frame arranged to move vertically in said guides, a hollow screw-threaded bolt to raise and lower said frame and an internal screw-threaded bolt to secure the die therein, all constructed substantially 15 as shown and described.

3. An improved die-holder for wire-drawing machines consisting of a base or bed with means for pivotally connecting parallel guides therewith, parallel guides pivotally 20 connected with said bed, a yoke to connect said guides, a forked brace to regulate the angle of said guides, and provided with means

for adjustably securing it to said base, a die-holding frame arranged to move in said guides, with means for moving it and means for securing said die in said frame, substantially 25 as shown and described.

4. In a die-holder for wire-drawing machines having guides for the die-frame and a die-frame to slide in said guides, improved 30 means for operating said parts, consisting of a hollow internally and externally screw-threaded bolt to move said die-frame, and a screw-threaded bolt within said hollow bolt to lock the die in the frame, substantially as 35 shown and described.

In testimony that I claim the above I hereunto set my hand in the presence of two subscribing witnesses.

JOHN W. HAWKINS.

In presence of—

C. P. HUMPHREY,
C. E. HUMPHREY.
